UNITED STATES PATENT OFFICE.

BENJAMIN S. McCLELLAN, OF CHICAGO, ILLINOIS.

WINDOW CONSTRUCTION.

1,051,146.

Specification of Letters Patent. Patented Jan. 21, 1913.

Application filed April 12, 1910. Serial No. 555,106.

To all whom it may concern:

Be it known that I, BENJAMIN S. McCLELLAN, a citizen of the United States, and residing at Chicago, in the county of Cook and State of Illinois, have invented a new and useful Improvement in Window Constructions, of which the following is a complete specification.

Heretofore in cars having metallic window frames it has been customary to provide the racks for the sash locks by forming apertures in the inner or rear walls of the guideways, into which apertures the lock bolts project to hold the sash in adjusted position. Such construction is objectionable for the reason that the apertures must be formed with great accuracy to prevent the bolts from lateral movement therein, since if they are not so formed the sash will rattle in the guideways. Also, when the apertures are formed with a downward and lateral incline for the lock bolts, so that the gravity of the sash may be utilized to force the sash against the stops, it has been found that the metal in which the apertures are formed is usually so thin that excessive wear is caused both on the incline and on the bolts. Furthermore, to punch the apertures is an expensive operation, requiring great care and skill in order to turn out a marketable product.

The main objects of the invention are to provide a metallic window construction having a rack bar in each guideway, which rack bars are secured to the inner wall of the guideway, and protrude from said wall into the guideway toward the sash; to provide a metallic window construction having relatively deep guideways for the sash to permit the insertion of the rack bars between the edges of the sash and the rear of the guideways; to provide a metallic window construction in which the locking bolts are afforded a broad bearing surface, and the necessity of aperturing the frame to receive the locking bolts is entirely obviated; and to provide a window construction adapted to prevent or absorb the noise usually caused by the sash lock bolts when the sash is being raised.

A specific construction embodying the invention is illustrated in the accompanying drawings, in which:

Figure 1 is a fragmentary, horizontal section of a window construction embodied in

this invention. Fig. 2 is a fragmentary view, partly in section, looking into the guideway for the sash. Fig. 3 is a fragmentary side elevation of the rack bar, looking from the outer side of the window. Fig. 4 is a fragmentary, horizontal section of a slightly modified form of window construction.

In the construction shown the metallic window frame 1 is formed to provide an integral outer stop 2, and a comparatively deep guideway 3 for the sash 4. One side wall of the guideway is formed by the edge or side 5 of the stop 2, and the rear or inner wall 6 of the guideway is integrally connected with the stop 2 and is spaced a considerable distance from the edge of the sash 4.

The inner window stop 7 is bolted to the post 8 and forms the other side of the guideway. The side of the stop 7 adjacent to the guideway is beveled at 9, and the angle bar 10 has one flange secured between the stop and the post, and the other flange lies flat against said beveled surface 9. A flexible weather strip 11 is secured at one edge to the edge of the sash by means of a T bar 12 and its free edge overlaps the adjacent flange of the bar 10 and bridges over the joint between the sash and the stop 7. The flange 13 of the T bar overlaps the outer face of the sash, and the flange 14 extends along the edge 5 of the stop 2, and together with the flange 13 provides a bearing surface or wear plate to protect the sash from wear against the stop.

Rigidly secured to the inner or rear wall 6 of each guideway and projecting into the guideway from said wall is the rack bar 15 for the sash lock. Said rack bar may be of any preferred form but preferably it is provided with downwardly and laterally inclined shoulders 16 upon which the bolt 17 of the sash lock rests when the bolt is in locking position, and which, by reason of the gravity of the sash, act to force the wear plates on the sash firmly against the stop 2. Beneath each of said shoulders, with the exception of the two lower ones, is an inclined surface 18 on the face of the rack adjacent to the sash. Said inclined surfaces 18 extend from the rear portion of the rack bar forwardly toward the sash and act to retract the lock bolts 17 when the sash is raised. Above the lower shoul-

der 16 is a shoulder 19 against which the bolt 17 may engage to lock the sash in closed position. The rack bars 15 are preferably secured to the guideways by means of screws 20 which extend through the wall 6 and into the post.

For the purpose of deadening the noise which would be occasioned by the lock bolts 17 traveling over the beveled surfaces 18 10 when the sash is being raised, especially in metallic window constructions, a strip of felt, rubber or other suitable material 21 is placed between each rack bar and the wall 6 of the guideway. The strips serve to absorb the sound and prevent unnecessary noise.

If preferred the angle bar 22 may be employed to secure the weather strip 11 to the sash, as shown in Fig. 4, in which case 20 the stop 2 is constructed of sufficient depth to overlap the edge of the sash, and one flange of the angle bar provides the wear plate for the sash.

By attaching the rack bar to the inner 25 wall of the guideway for the sash and forming the guideway deep enough to permit the rack to lie intermediate the wall and the edge of the sash, the construction of metallic frames is greatly simplified and cheapened. Furthermore a much broader metallic 30 bearing for the lock bolts can be obtained by the use of rack bars than can be obtained where the wall 6 of the guideway is apertured to receive the bolts, since the metal 35 forming such wall is usually comparatively thin.

Obviously many details of the form and construction shown may be varied without departing from the scope of the claims.

40 I claim:

1. A window construction, comprising a window frame having a guideway therein, a wooden sash, a rack bar consisting of a flat metal strip located in said guideway 45 and secured flatwise to the inner wall of said guideway in spaced relation to the side walls thereof, a metallic member secured to the edge of said sash facing said guideway and provided with a laterally extending integral flange constituting a wear plate projecting into said guideway and adapted to bear against one of the side walls thereof, the edge of said flange terminating in the space between the rack bar and the side wall 50 of the guideway, and a locking bolt mount-

ed on the sash and adapted to engage said rack bar.

2. A window construction, comprising a window frame having a guideway therein, a wooden sash, a metallic member secured to the edge of said sash facing said guideway and provided with a laterally extending integral flange constituting a wear plate projecting into said guideway and adapted to bear against one of the side walls thereof, 60 a rack bar consisting of a flat metal strip located in said guideway and secured flatwise to the inner wall thereof, said rack bar being provided with a plurality of longitudinally spaced notches or openings extending through the edge of said rack bar adjacent the side wall of the guideway in contact with the said wear plate, said notches forming shoulders inclined outwardly and downwardly toward the wear plate, and a 65 locking bolt mounted on the sash adapted to seat on said inclined shoulders for holding the wear plate in close contact with the side wall of the guideway.

3. A window construction, comprising a 80 metallic window frame having a guideway therein, a wooden sash, a flat metallic member secured to the edge of said sash facing said guideway and provided at one end with a transversely extending integral 85 flange constituting a wear plate for said sash, one part of said flange projecting into said guideway and adapted to bear against one of the side walls thereof and the opposite part of said flange overlapping the outer 90 face of the sash, a flat metal strip constituting a rack bar located in said guideway and secured flatwise to the inner wall thereof, a strip of felt interposed between said rack bar and the inner wall of said guideway, a 95 locking bolt mounted on said sash and adapted to engage said rack bar, and a weather strip secured to said sash between said flat metal member and the edge of the same and having its free end bearing against 100 the side wall of the guideway opposite the wear plate.

In testimony whereof I have hereunto subscribed my name in the presence of two witnesses.

BENJAMIN S. McCLELLAN.
